UNITED STATES PATENT OFFICE.

WALTER I. SHUGG, OF NEW HAVEN, CONNECTICUT, ASSIGNOR TO WINCHESTER
REPEATING ARMS CO., OF NEW HAVEN, CONNECTICUT, A CORPORATION.

DESIGN FOR A LABEL.

52,812.

Specification for Design.

Patented Dec. 24, 1918.

Application filed August 26, 1918. Serial No. 251,590. Term of patent 14 years.

To all whom it may concern:

Be it known that I, WALTER I. SHUGG, a citizen of the United States, residing at New Haven, in the county of New Haven and State of Connecticut, have invented a new, original, and ornamental Design for a Label, of which the following is a specification, reference being had to the accompanying drawing, forming part thereof.

The figure is a face view of a label showing my new design.

I claim:

The ornamental design for a label, as shown.

WALTER I. SHUGG.

Witnesses:

ERIK PALMER,
ARTHUR W. EARLE.
